Primary Examiner — Cynthia R Underwood

(74) Attorney, Agent, or Firm — Jeffer Mangels; Butler & Mitchell LLP; Brennan C. Swain, Esq.

(57) **CLAIM**

The ornamental design for a connector, as shown and described.

DESCRIPTION

FIG. 1 is a perspective view of the present invention; FIG. 2 is a right side elevational view of the present invention shown in FIG. 1, the left side elevational view being a mirror image thereof;

FIG. 3 is a front elevational view of the present invention shown in FIG. 1, the rear elevational view being a mirror image thereof; and,

FIG. 4 is a bottom plan view of the present invention shown in FIG. 1.

1 Claim, 4 Drawing Sheets(56)
